UNITED STATES PATENT OFFICE.

EMILE SINS, OF PARIS, FRANCE, ASSIGNOR TO CHENEY BROTHERS, OF SOUTH MANCHESTER, CONNECTICUT, A CORPORATION OF CONNECTICUT.

DESIGN FOR TEXTILE FABRIC.

40,937.

Specification for Design.

Patented Oct. 11, 1910.

Application filed May 21, 1910. Serial No. 562,786. Term of patent $3\frac{1}{2}$ years.

To all whom it may concern:

Be it known that I, EMILE SINS, a citizen of the French Republic, residing at Paris, France, have invented a new, original, and ornamental Design for Textile Fabrics, of which the following is a specification, reference being had to the accompanying drawing, forming part thereof.

The drawing illustrates a section or portion of a fabric embodying my new design.

I claim:

The ornamental design for a textile fabric, as shown.

EMILE SINS.
